UNITED STATES PATENT OFFICE.

LUIS MANZANO, OF HUELVA, SPAIN.

BUFFER FOR CAR-COUPINGS.

1,095,011.

Specification of Letters Patent. Patented Apr. 28, 1914.

Application filed May 18, 1912. Serial No. 698,306.

To all whom it may concern:

Be it known that I, LUIS MANZANO, a subject of the King of Spain, and resident of Huelva, Spain, have invented certain new and useful Improvements in Buffers for Car-Couplings, of which the following is a specification.

The present invention relates particularly to buffers for car couplers, the object being 10 to provide simple and effective means for absorbing undue shocks when cars are coupled.

The invention also relates to improvements in the details of construction and arrangement of parts which will be herein-after described and particularly pointed out in the claims.

In the accompanying drawing: Figure 1 is a partial side elevation and section of my 20 improvement. Fig. 2 is a perspective view of a coupler equipped with my member, parts being broken away. Fig. 3 is a plan view partially in section. Fig. 4 is a detail perspective view of the outside buffer. Fig. 25 5 is a detail view of the forward abutment. Fig. 6 is a detail perspective view of the inside buffer member.

50 indicates a car, provided with supports 51, in which my improved buffer is mounted, 30 the buffer comprising a two part draw bar.

21^b, indicates a member of the draw bar, formed with a square portion 21', from which extends a reduced stem 21. On the stem, and fitting against the inner end of 35 the square portion 21', is an abutment 29, formed with seats or depressions 31^x, and on the inner end of the stem is a second abutment 53, mounted in one of the supports 51. The abutment 53, is confined in position by 40 a washer and nut 54, on the end of the stem, and a spring 30, is interposed between the said abutments 29 and 53. The forward end of the member 21^b, is horizontally bifurcated, as at 21^x, the bifurcated portions having vertical, aligned openings 4. In rear of 45 the bifurcated portion 21^x, the member 21^b, is formed on its upper and lower horizontal surfaces with shoulders 24^x, and in alignment with said shoulders, and extending outwardly from both sides of the member 21^b, are lugs 24.

22 indicates an outer member, comprising a coupling head 3, and two rearwardly projecting side bars 22', which fit closely 55 against the sides of the member 21^b. The side bars 22' are provided on their upper

and lower edges, in rear of the head 3, with lugs 22^x, which coöperate with the lugs 24, in the operation of the buffer. The rear ends of the side bars 22', are provided with reduced extensions 31, which fit in the seats 31^x, in the abutment 29. The side bars 22', are formed with elongated slots 27, in which the ends of a pin 5' fit, said pin being mounted in lugs 22ⁱ on the member 21^b.

A locking pin 2 is mounted on the pin 5, between the lugs 22ⁱ, and extends through the openings 4.

In operation, a coupling link 1, serves as a connection between the couplers of adjacent 70 cars as shown in the drawings.

In normal position, the spring 30, will hold the two members 22 and 21^b in position, so that the lugs 22^x, and 24 will be spaced apart, and the pin 5, will be against 75 the rear walls of the slots 27. When pressure on a coupler head is applied, the member 22 will be forced inwardly, which through the medium of the abutment 29, will compress the spring 30. If the pressure is 80 continued, the walls of the slot 27, will contact with pin 5, and the lugs 22^x, and 24, will contact, and then both members 21^b, and 22, will simultaneously move against the tension of spring 30, and thereby distribute the 85 strain.

Having now fully described my said invention, what I claim and desire to secure by Letters Patent, is:

1. In an apparatus of the class described, 90 the combination of a support, a two part draw bar mounted in the support and comprising two members, one member having a stem, an abutment mounted on the stem, a second abutment on the stem, and against 95 which both members abut, a spring interposed between the abutments, the member having the stem also having lugs, the companion member having side arms which engage the member with the stem, and said 100 companion member having lugs which co-operate with the lugs on the member having the stem.

2. In an apparatus of the class described, 105 the combination of a draw bar comprising an outer member and an inner member, the outer member having two parallel arms formed at their inner ends with studs, said outer member having lugs and slotted ears near the forward end, the inner member having perforated ears and lugs near its forward end the ears on both members being 110

adjacent each other, and the lugs on both members coöperating, a pin connecting the ears; the lugs being normally spaced apart, a reduced stem extending from the inner member, an abutment mounted on the stem and against which the inner member and the outer member abut, said abutment having seats in which the studs fit, a second abutment on the stem, means for retaining the second abutment on the stem, and a spring interposed on the stem and confined between the abutments.

3. In an apparatus of the class described, a draw bar comprising inner and outer members, the outer member having a hollow head formed with slotted ears and lugs adjacent said ears, the inner member having a bifurcated head which fits in and forms part of the hollow head on the outer member, the inner member, having perforated

ears which register with the slotted ears, and lateral lugs in rear of said perforated ears, the lugs on the inner and outer members being in the same path of movement and normally spaced from each other, a pin connecting the slotted and perforated ears, a stem extending from the inner member, an abutment mounted on the stem and against which the inner end of the abutment bears, a second abutment mounted on the stem, means for retaining the said second abutment in position on the stem, and a spring interposed between the abutments.

In testimony whereof I have hereunto set my hand in presence of two witnesses.

LUIS MANZANO.
